RAILWAY TRAFFIC CONTROLLING APPARATUS

Application filed June 24, 1931. Serial No. 546,514.

Our invention relates to railway traffic controlling apparatus, and particularly to apparatus of the type involving tripping devices located in the trackway and cooperating with car-carried apparatus to apply the brakes under unsafe traffic conditions in advance.

One feature of our invention is the provision of novel and improved means for permitting the driver of the car to clear a tripping device under unsafe traffic conditions in advance and for simultaneously imposing a safe low speed limit on the car.

We will describe two forms of apparatus embodying our invention, and will then point out the novel features thereof in claims.

In the accompanying drawings, Fig. 1 is a diagrammatic view showing one form of apparatus embodying our invention. Fig. 2 is a similar view showing a modified form of the apparatus illustrated in Fig. 1, and also embodying our invention. Fig. 3 is a plan view of a car showing one arrangement of trip arms and contact shoes which may be employed in connection with the apparatus shown in Figs. 1 and 2.

Similar reference characters refer to similar parts in each of the views.

Referring first to Fig. 1, the reference characters 2 and 2^a designate the rails of a railway track along which traffic normally moves in the direction indicated by the arrow. The rail 2^a is divided, by means of insulated joints 3, to form a plurality of successive track sections of which only one section T is shown in the drawing. This section is provided with a track circuit comprising a track relay A, and a suitable source of current which as here illustrated, is a transformer V, the secondary 31 of which is connected across the rails in series with the usual current limiting impedance 32. The primary 33 of transformer V is constantly supplied with alternating current from the terminals BX and CX of a suitable source not shown in the drawing. Section T is also provided with a home relay H which may be controlled in any suitable manner, the controlling circuit for this relay being omitted in order to simplify

the drawing. It is understood that relay H is energized when and only when track relay A is energized and traffic conditions in advance of the section shown in the drawing are safe.

Associated with the track section T is an element D constituting a combined tripping device and contact arm. This element is biased to a projected position wherein it is illustrated in dash lines, but may be moved to a retracted position when an operating mechanism E is energized. Mechanism E is energized whenever the home relay H is energized, the circuit being from terminal BX of a source of alternating current, through front contact 6 of relay H, and the operating mechanism E to terminal CX of the same source. Mechanism E is provided with the usual retaining circuit including a back contact 9 of track relay A and a contact 8 which is closed when and only when the element D is in its retracted position; the purpose of this retaining circuit is to prevent the element D from being released while a train is passing over it. Associated with the mechanism E is a clearing relay F which is normally de-energized, but which may be energized momentarily from a source of current carried by the car as hereinafter explained. When relay F is energized, an auxiliary circuit for the operating mechanism E will be closed, which circuit includes a front contact 7 of relay F and will be obvious from the drawing.

Located on the car is a trip arm R which controls a brake application valve 26. The trip arm R is arranged to be operated by the trackway element D to open the valve 26 when the element D is in its projected position but not when it is in its retracted position. Also located on the car in advance of the trip arm R is a contact shoe K which normally occupies a retracted position wherein it is shown in the drawing. This shoe may be moved to a first projected position wherein it will engage the trackway element D when the latter is in its projected position but not when the element is in its retracted position. The shoe K may also be moved to a second projected position wherein it will engage the

trackway element D when the latter is in its retracted position. The shoe K is controlled by a fluid pressure device L, which in turn is controlled by a manually operable valve device M. When the valve device M is in its middle position, wherein it is shown in the drawing, fluid pressure is not supplied to the fluid pressure device L, and the contact shoe K then occupies its retracted position under the influence of a spring 14. When the valve device M is moved in counter-clockwise direction from the position in which it is shown in the drawing, fluid pressure will be supplied from a suitable source through a pipe 15 and rotary member 24 of the valve device M to the upper end of the cylinder 28 of the motor L. This fluid pressure will move a piston 13 downwardly, and this piston in turn will move the stem 11 and the shoe K to their first projected positions. This position is determined by the engagement of piston 13 with a shoulder 27 in the cylinder 28 of the motor L. When the valve M is moved in clockwise direction from the position in which it is shown in the drawing, fluid pressure will be supplied to the cylinder of motor L between pistons 13 and 12, and this fluid pressure will cause piston 12 to move downwardly thereby moving stem 11 and shoe K to their second projected positions. This position of the shoe is determined by the engagement of piston 12 with the lower end of the cylinder 28, and it will be observed that the stroke of piston 12 is longer than the stroke of piston 13.

When the shoe K is in its retracted position, two contacts 18 and 20 are closed. When the shoe moves to its first projected position these contacts will be opened, and two other contacts 19 and 21 will be closed. When the shoe is moved to its second projected position all four contacts 18, 19, 20 and 21 will be open, and a fifth contact 22 will be closed.

The reference character N designates a train-carried speed controlling relay. This relay is provided with a stick circuit which passes from a battery S, through contact 18, the lower winding of relay N, front contact 17 of relay N and contact 20 to battery S. It will be seen that this circuit is closed when and only when relay N is energized and the shoe K is in its retracted position. When relay N is energized, a brake application valve Q is energized by virtue of a circuit which includes front point of contact 23 of relay N, and a source of current the terminals of which are designated B and C. Under this condition, the car may travel at any desired speed. When relay N is deenergized, the circuit for brake valve Q is from terminal B, through contact 30 operated by a speed responsive device P, back point of contact 23 of relay N, and the winding of valve Q to terminal C. Contact 30 is arranged to open

when the speed of the car is above a safe low value, such, for example, as 15 miles per hour, and, consequently, it will be seen that when relay N is deenergized, a safe low speed limit is imposed on the car.

The operation of the apparatus is as follows: Assuming that home relay H is energized, so that the trackway element D is in its retracted position, this element will be out of the path of the trip arm R, and, consequently, the element will have no influence on a car entering track section T. If, however, home relay H is deenergized, so that the trackway element D is in its projected position, then unless the operator of the car takes suitable action, the element D will coat with the trip arm R to cause an automatic application of the brakes. If, however, the operator moves the contact shoe K to its first projected position, then when this shoe engages the element D, a circuit will be closed to energize the clearing relay F. This circuit is from battery S, through contact 21, shoe K, trackway element D, back contact 5 of relay H, winding of relay F, ground at G, ground at G¹ on the car, and contact 19 to battery S. The closing of relay F will energize the operating mechanism E to retract the element D before this element contacts with the car-carried trip arm R, and the element D will then remain in its retracted position, due to the retaining circuit for E through back contact 9 of relay A, until the car leaves section T. The movement of the shoe K to its first projected position will, however, open the stick circuit for relay N, and this relay will remain deenergized even if the shoe K is restored to its retracted position. It follows that a low speed limit will be imposed on the car while the car is traversing track section T.

When the car enters a section the element D for which is in the retracted position, the operator may move the contact shoe K to its second projected position, thereby closing a pick-up circuit for car-carried relay N. This circuit is from terminal BX in the trackway, through front point of contact 5 of relay H, trackway element D, contact shoe K, contact 22, primary of a transformer 15, and ground G² to terminal CX in the trackway. The secondary of transformer 15 is connected with the upper or pick-up winding of relay N through a rectifier 16, so that this relay will then become energized. The contact shoe K may then be restored to its retracted position, thereby closing the stick circuit for relay N. Relay N should be sufficiently slow-releasing in character in order to keep it closed during the transition from its pick-up circuit to its stick circuit. The closing of stick relay N will remove the speed limit, so that the car may then proceed without restriction until it encounters another trackway element D in projected position.

Referring now to Fig. 2, as here shown, the contact shoe K is controlled by a fluid pressure device L^a which, in turn, is controlled by a valve device M^a. When the rotary member of the valve device M^a occupies the position in which it is illustrated in the drawing, the upper end of the cylinder 28^a of the fluid pressure device L^a is connected with atmosphere through a pipe 41, rotary member 40 of valve device M^a, and pipe 42. Under this condition, the piston 12 is moved, by means of the spring 14 to an upper position in which it is illustrated in the drawing. The parts are so proportioned that when the piston 12 occupies this position, the shoe K will occupy a retracted position in which it will engage the trackway element D in its projected position, but not when this element is in its retracted position. When the valve device M^a is moved in a counter-clockwise direction from the position in which it is illustrated in the drawing, fluid pressure will be supplied to the upper end of cylinder 28^a from a suitable source not shown in the drawing, through a pipe 43, rotary member 40 of valve device M^a and pipe 41. This fluid pressure will cause piston 12 to move downwardly until the piston engages the lower end of the cylinder, therefore by moving stem 11 downwardly, and hence moving shoe K to a projected position in which it will engage the trackway element D in its retracted position.

The reference character W designates a fluid pressure controlled brake application valve which is connected with the brake pipe by means of a pipe 52. As here shown, this valve comprises a valve member 47 which is biased by a spring 48 to a lower position in which it closes an exhaust port 49 leading to atmosphere. The pressure on the two sides of the valve member 47 is equalized by a small equalizing port 50 in the side wall of the valve whereby, when the pipe 51 connected with the upper end of the valve W is closed, the pressure is equalized and the valve member occupies its lower position wherein the exhaust port 49 is closed. If the pipe 51 is opened to atmosphere, however, the pressure on the upper side of the valve member 47 will be reduced, whereupon the brake pipe pressure on the lower side of this member will cause the member to be moved upwardly to open the brake pipe to atmosphere through exhaust port 49, thus applying the brakes. Member 47 will then remain in its upper position until the pressure in the brake pipe is reduced to a very small value whereupon this member will be restored to its lower or closing position by the action of the spring 48.

Pipe 51 is connected with a pipe 53 through a magnet valve Q¹ which is closed when its winding 55 is energized, but not when its winding 55 is deenergized, and the pipe 53,

in turn, is connected with atmosphere through a pilot valve Z and a port 54. The pilot valve Z is operated by the speed responsive device P, and is arranged to open when the speed of the car is above a safe low value, such for example as fifteen miles per hour. It will be apparent, therefore, that when valve Q is energized, the pipe 51 is blanked, and the car may then travel at any desired speed, but that, when the valve Q¹ is deenergized, if the speed of the car exceeds the speed at which the pilot valve Z opens, pipe 51 will become connected with atmosphere through valve Q¹, pipe 53, valve Z, and port 54, and valve W will then open and will apply the brakes. It follows, therefore, that a safe low speed limit is imposed on the car when valve Q¹ is deenergized but not when this valve is energized.

Valve Q¹ is provided with a circuit which is controlled by the speed controlling relay N, and which is closed only when relay N is energized, this circuit passing from battery S through front point of contact 40 of relay N, and winding 55 of valve Q¹ back to battery S. Relay N is normally energized by virtue of a stick circuit which passes from battery S through front point of contact 40 of relay N, contact 44 of a manually controlled acknowledging switch U, and the lower winding of relay N back to battery S. Contact 44 of acknowledging switch U is normally closed, but is arranged to become open when switch U is operated. It will be seen, therefore, that relay N will become deenergized when switch U is operated.

Switch U is provided, in addition to the contact 44, with a normally closed contact 45 which becomes opened when the switch is operated, and with a normally open contact 46 which becomes closed when the switch is operated. The function of the contacts 45 and 46 will become apparent as the description proceeds.

Considering now the trackway portion of the apparatus shown in Fig. 2, the clearing relay, which is here designated F¹, is provided with a pick-up winding 38 and holding winding 39. The pick-up winding 38 is arranged to be at times momentarily energized from the train-carried battery S over a pick-up circuit which can best be described while explaining the operation of the apparatus as a whole. The holding winding 39 is included in a stick circuit for relay F¹, which stick circuit passes from terminal X of a suitable source of current not shown in the drawing through back contact 34 of track relay A, front contact 35 of relay F¹, and the holding winding 39 to terminal Y of the source. When relay F¹ is energized, it completes an auxiliary circuit for the mechanism E which is similar to the circuit previously described in connection with Fig. 1, with the exception that this circuit is controlled by front con-

tact 56 of relay F^1 instead of by contact 7 of relay F as shown in Fig. 1. The remainder of the trackway apparatus shown in Fig. 2 is similar to that shown in Fig. 1 with the exception that mechanism E is provided with an auxiliary clearing circuit which causes mechanism E to automatically become energized and move the trackway element D to its retracted position if a train which is moving in the opposite direction from the normal direction of traffic enters section T from the right for any reason when the section T^1 in rear of section T is unoccupied. This auxiliary clearing circuit passes from terminal BX through front contact 36 of the track relay A^1 for section T^1 , back contact 37 of track relay A, and mechanism E to terminal CX.

In explaining the operation of the apparatus shown in Fig. 2 as a whole, I will first assume that when the car enters section T, home relay H is energized. Under these conditions, the trackway element D will be held in its retracted position by virtue of the circuit for the mechanism E through contact 6 of relay H, and the element D will therefore have no influence on the car, so that the car may proceed through the section at any desired speed.

I will next assume that when the car enters section T, relay H is deenergized, so that the trackway element D is in its projected position. Under these conditions, unless the operator of the car takes suitable action, the element D will coat with the trip arm R to cause an automatic application of the brakes. If, however, the operator is alert and operates the acknowledging switch U before the shoe K passes the trackway element D, and subsequently holds it in its operated position while the shoe is passing the trackway element, an automatic application of the brakes will be prevented in a manner which I will now explain. When switch U is operated, the stick circuit for relay N will become interrupted at contact 44 of switch U, and relay N will therefore become deenergized and will deenergize valve Q^1 . As previously described, when valve Q^1 becomes deenergized, pipe 51 is connected with pipe 53, and a low speed limit will therefore then be imposed on the car. With relay N deenergized, so that the back point of its contact 40 is closed, and with contact 46 of acknowledging switch U closed, the engagement of the shoe K with the trackway element D will complete the pick-up circuit for relay F^1 previously referred to, this circuit passing from battery S through back point of contact 40 of relay N, contact 46 of acknowledging switch U, shoe K, trackway element D, back point of contact 5 of relay H, pick-up winding 38 of relay F^1 , ground at G, and ground at G^1 on the car back to battery S. Due to this pick-up circuit, relay F^1 will become momentarily en-

ergized and will complete its stick circuit as well as the auxiliary circuit for the mechanism E. When the auxiliary circuit for the mechanism E is completed, this mechanism will become energized and will move the element D to its retracted position before this element coats with the car-carried trip arm R. When the element D moves to its retracted position, it will close contact 8, which in turn will complete the retaining circuit for mechanism E. The function of the stick circuit for relay F^1 is to insure that when relay F^1 becomes energized due to the momentary closing of its pick-up circuit, it will subsequently remain energized for an interval of time which is long enough to cause mechanism E to move element D to its full retracted position in which contact 8 is closed. When the switch U is now restored to its normal position, relay N will remain deenergized, and it follows, therefore, that the low speed limit will continue to be imposed on the car as long as the car remains in section T. When the car leaves section T, the subsequent energization of track relay A will deenergize relay F^1 which, in turn, will deenergize the mechanism E. The trackway portion of the apparatus will then be restored to the condition which it occupied when the car entered the section.

In order to restore the car-carried apparatus to its normal position, the operator may operate the valve M^a to move the shoe K to its projected position while the car is passing a trackway element D in its retracted position. When this is done, a pick-up circuit for relay N will be completed which passes from the right-hand terminal of secondary 31 of transformer V^1 , through front point of contact 5 of home relay H, trackway element D, contact shoe K, contact 45 of acknowledging switch U, rectifier 16, the winding of relay N, rectifier 16 to ground at G^2 , and rail 2 to the left-hand side of secondary 31 of transformer V^1 . Due to this pick-up circuit, relay N will become energized and will close its stick circuit. The shoe K may then be restored to its retracted position, and relay N will remain energized. The energization of relay N will energize valve Q^1 , which will remove the speed limit, and the car may then proceed without restriction until it encounters another trackway element D in its projected position.

As illustrated in Fig. 3, each side of the car may be provided with a contact shoe K and a trip arm R, these elements being so arranged that regardless of the direction in which the car is moving, the contact shoe K will always encounter the trackway element D before the trip arm R encounters this element.

Although we have herein shown and described only two forms of apparatus embodying our invention, it is understood that vari-

ous changes and modifications may be made therein within the scope of the appended claims without departing from the spirit and scope of our invention.

5 Having thus described our invention, what we claim is:

1. Railway traffic controlling apparatus comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, means for at times moving said trackway element to its retracted position in response to engagement of said contact shoe and said trackway element in its projected position and for imposing a low speed limit on the car, and means for removing such speed limit restriction in response to engagement of said contact shoe and the trackway element in its retracted position.

2. Railway traffic controlling apparatus comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a car-carried contact shoe normally occupying a retracted position, manually controlled means for moving said shoe to a first projected position wherein it will engage said trackway element when the latter is in its projected position but not in its retracted position and for moving said shoe to a second projected position wherein it will engage the trackway element in the retracted position of the latter, means operating to move said trackway element to its retracted position in response to engagement of the contact shoe in its first projected position and the trackway element in its projected position, means responsive to movement of said contact shoe to its first projected position for imposing a low speed limit on the car, and means for removing such speed limit restriction in response to engagement of said contact shoe in its second projected position and the trackway element in its retracted position.

3. Railway traffic controlling apparatus comprising an element constituting a combined tripping device and contact arm located

in the trackway and biased to a projected position, a home relay energized only under safe traffic conditions in advance, a normally deenergized clearing relay, means for moving said element to a retracted position when either said home relay or said clearing relay is energized, a car-carried brake applying arm arranged to be operated by said trackway element when the latter is in its projected position but not when it is in its retracted position, a car-carried contact shoe normally occupying a retracted position, manually controlled means for moving said shoe to a first projected position wherein it will engage said trackway element in its projected position but not in retracted position and for moving said shoe to a second projected position wherein it will engage said trackway element in retracted position, a car-carried speed relay, a stick circuit for said speed relay closed only when the relay itself is closed and said shoe is in retracted position, a circuit for said clearing relay including a car-carried source of current and closed only when the shoe in its first projected position engages the trackway element in its projected position, a pick-up circuit for said speed relay including a trackway source of current and closed only when said shoe in its second projected position engages said trackway element in its retracted position provided said home relay is energized, and means for imposing a safe low speed limit on the car when said speed relay is deenergized but not when it is energized.

4. Railway traffic controlling apparatus comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a car-carrying contact shoe normally occupying a retracted position in which it will engage said trackway element when the latter is in its projected position but not in its retracted position, manually controlled means for moving said trackway element to its retracted position in response to engagement of the contact shoe and the trackway element in its projected position and for imposing a low speed limit on the car, and means for removing such speed limit restriction in response to engagement of said contact shoe in its projected position and said trackway element in its retracted position.

5. Railway traffic controlling apparatus comprising an element constituting a com-

bined tripping device and contact arm located in the trackway and movable to a retracted or a projected position according as traffic conditions in advance are safe or 5 unsafe, a car-carried brake applying trip arm arranged to be operated by said trackway element when the latter is in its projected position but not when it is in its retracted position, a manually controlled car-carried 10 contact shoe adapted to at times engage said trackway element in its projected position and to at other times engage said trackway element in its retracted position, an acknowledging switch on the car, means controlled 15 by said switch for moving said trackway element to its retracted position in response to engagement of the contact shoe and the trackway element in its projected position and for imposing a low speed limit on the car, 20 and means for removing such speed limit restriction in response to engagement of said contact shoe and the trackway element in its retracted position.

6. Railway traffic controlling apparatus 25 comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car-carried 30 contact shoe adapted to at times engage said trackway element in its projected position and to at other times engage said trackway element in its retracted position, an acknowledging switch on the car, a normally energized magnet valve on the car, means controlled 35 by said acknowledging switch and effective, when said switch is operated, for deenergizing said valve, means controlled by said valve for imposing a low speed restriction on the car, means controlled by said acknowledging switch and effective when and only when said shoe engages said trackway element in its projected position for moving said trackway element to its retracted position, and means effective 40 when said shoe engages said trackway element in its retracted position for reenergizing said magnet valve.

7. Railway traffic controlling apparatus 45 comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car-carried 50 contact shoe adapted to at times engage said

trackway element in its projected position and to at other times engage said trackway element in its retracted position, an acknowledging switch on the car, a normally energized magnet valve on the car, means controlled by said acknowledging switch and effective, when said switch is operated, for deenergizing said valve, means effective when said valve becomes deenergized for imposing a low speed restriction on the car, means controlled by said acknowledging switch and effective when and only when said shoe engages said trackway element in its projected position for moving said trackway element to its retracted position, and means effective 75 when said shoe engages said trackway element in its retracted position for reenergizing said magnet valve.

8. Railway traffic controlling apparatus 80 comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, an acknowledging switch on the car, a pilot valve on the car controlled in accordance with the speed of the car, a magnet valve on the car, a brake application valve on the car controlled by said magnet valve and by said pilot valve, a speed controlling relay on the car, means controlled by said relay for controlling said magnet valve, an acknowledging switch on the car, a stick circuit for said speed controlling relay controlled by a front contact of said speed controlling relay and by said acknowledging switch, means controlled by said acknowledging switch for moving said trackway element to its retracted position in response to engagement of the contact shoe and the trackway element in its projected position, and a pick-up circuit for said speed controlling relay arranged to be closed when said contact shoe engages said trackway element in its retracted position.

9. Railway traffic controlling apparatus 120 comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car- 125

carried contact shoe adapted to at times engage said trackway element in its projected position and to at other times engage said trackway element in its retracted position, an acknowledging switch on the car, a pilot valve on the car controlled in accordance with the speed of the car, a magnet valve on the car, a brake application valve on the car controlled by said magnet valve and by said pilot valve, a speed controlling relay on the car, means controlled by said relay for controlling said magnet valve, an acknowledging switch on the car, a stick circuit for said speed controlling relay controlled by a front contact of said speed controlling relay and by said acknowledging switch, means controlled by said acknowledging switch and by said speed controlling relay for moving said trackway element to its retracted position in response to engagement of the contact shoe and the trackway element in its projected position, and a pick-up circuit for said speed controlling relay controlled by said acknowledging switch and arranged to be closed when and only when said contact shoe engages said trackway element in its retracted position.

10. Railway traffic controlling apparatus comprising an element constituting a combined tripping device and contact arm located in the trackway and movable to a retracted or a projected position according as traffic conditions in advance are safe or unsafe, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, an acknowledging switch on the car, a pilot valve on the car controlled in accordance with the speed of the car, a magnet valve on the car, a brake application valve on the car, means effective when said magnet valve is deenergized for controlling said brake application valve by said pilot valve, a speed controlling relay on the car, means for energizing said magnet valve when and only when said relay is energized, an acknowledging switch on the car, a stick circuit for said speed controlling relay controlled by a front contact of said speed controlling relay and by said acknowledging switch, means controlled by said acknowledging switch for moving said trackway element to its retracted position in response to engagement of the contact shoe and the trackway element in its projected position, and a pick-up circuit for said speed controlling relay arranged to be closed when said contact shoe engages said trackway element in the retracted position of the trackway element.

11. Railway traffic controlling apparatus comprising a stretch of railway track provided with a track circuit including a track relay, an element constituting a combined tripping device and contact arm located in the trackway and biased to a projected position, a home relay energized only under safe traffic conditions in advance, a normally de-energized clearing relay, means for moving said element to a retracted position when either said home relay or said clearing relay is energized, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, means on the car for energizing said clearing relay in response to engagement of said shoe and said trackway element in its projected position and for imposing a low speed limit on the car, and means for removing such speed limit restriction in response to engagement of said contact shoe and the trackway element in its retracted position.

12. Railway traffic controlling apparatus comprising a stretch of railway track provided with a track circuit including a track relay, an element constituting a combined tripping device and contact arm located in the trackway and biased to a projected position, a home relay energized only under safe traffic conditions in advance, a normally de-energized clearing relay, a stick circuit for said clearing relay including a back contact of said track relay and a front contact of said clearing relay, means for moving said element to a retracted position when either said home relay or said clearing relay is energized, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, means on the car for energizing said clearing relay in response to engagement of said shoe and said trackway element in its projected position and for imposing a low speed limit on the car, and means for removing such speed limit restriction in response to engagement of said contact shoe and the trackway element in its retracted position.

13. Railway traffic controlling apparatus comprising two adjacent sections of railway track over which traffic normally moves in both directions, a trackway element constituting a combined tripping device and contact arm associated with the forward section

- and biased to a projected position, means for automatically moving said arm to a retracted position if a car moving in the opposite direction from the normal direction of traffic enters the forward section when the rear section is unoccupied, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, means for moving said trackway element to its retracted position in response to engagement of said shoe and said trackway element in its projected position and for imposing a low speed limit on the car, and means for removing such speed limit restriction in response to engagement of said contact shoe and the trackway element in the retracted position of the latter.
14. Railway traffic controlling apparatus comprising two adjacent sections of railway track over which traffic normally moves in one direction, a track circuit for each section including a track relay, a trackway element constituting a combined tripping device and contact arm associated with the forward section and biased to a projected position, mechanism for moving said trackway element to a retracted position, a home relay associated with the forward section and energized only under safe traffic conditions in advance, a normally deenergized clearing relay associated with the forward section and provided with a pick-up and a holding winding, a first circuit for said mechanism including a front contact of said clearing relay, a second circuit for said mechanism including a front contact of the track relay for the rear section and a back contact of the track relay for the forward section, a contact controlled by said trackway element and arranged to be closed when and only when said trackway element occupies its retracted position, a third circuit for said mechanism including said trackway element controlled contact and a back contact of the track relay for the forward section, a fourth circuit for said mechanism including a front contact of said home relay, a stick circuit for said clearing relay including a front contact of said clearing relay and a back contact of the track relay for the forward section, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, means for at times momentarily energizing said clearing relay in response to engage-

ment of said shoe and said trackway element in its projected position and for simultaneously imposing a low speed limit on the car, and means for removing such speed limit restriction in response to engagement of said contact shoe and the trackway element in its retracted position.

15. Railway traffic controlling apparatus comprising two adjacent sections of railway track over which traffic normally moves in one direction, a track circuit for each section including a track relay and a source of current, a trackway element constituting a combined tripping device and contact arm associated with the forward section and biased to a projected position, mechanism for moving said trackway element to a retracted position, a home relay associated with the forward section and energized only under safe traffic conditions in advance, a normally deenergized clearing relay associated with the forward section and provided with a pick-up and a holding winding, a first circuit for said mechanism including a front contact of said clearing relay, a second circuit for said mechanism including a front contact of the track relay for the rear section and a back contact of the track relay for the forward section, a contact controlled by said trackway element and arranged to be closed when and only when said trackway element occupies its retracted position, a third circuit for said mechanism including said trackway element controlled contact and a back contact of the track relay for the forward section, a fourth circuit for said mechanism including a front contact of said home relay, a stick circuit for said clearing relay including a front contact of said clearing relay and a back contact of the track relay for the forward section, a car-carried brake applying trip arm arranged to be operated by said trackway element when the latter is in its projected position but not when it is in its retracted position, a manually controlled car-carried contact shoe adapted to at times engage said trackway element in its projected position and to at other times engage said trackway element in its retracted position, an acknowledging switch on the car provided with two normally closed contacts which become opened when the switch is operated and a normally open contact which becomes closed when the switch is operated, a speed controlling relay on the car; a stick circuit for said speed controlling relay including a car-carried source of current, a front contact of said speed controlling relay, and a first one of the normally closed contacts of said acknowledging switch; a pilot valve on the car responsive to the speed of the car, a magnet valve on the car, a brake applying valve on the car arranged to be controlled by said pilot valve when said magnet valve is deenergized but not when said magnet valve

is energized; a circuit for said magnet valve including a car-carried source of current and a front contact of said speed controlling relay; a pick-up circuit for said clearing relay including a car-carried source of current, a 5 back contact of said speed controlling relay, the normally open contact of said acknowledging switch, said shoe and said trackway element; and a pick-up circuit for said speed controlling relay including the source of current for the rear track section, a front contact of said home relay, said shoe, said trackway element, and the remaining normally closed contact of said acknowledging switch.

10 In testimony whereof we affix our signatures.

HOWARD A. THOMPSON.
FRANK H. NICHOLSON.
